E. K. BOTTLE

MANIFOLDING SALES BOOK

Filed July 5, 1922

INVENTOR
Edward K. Bottle,
BY
Dowell, Marfield & Dowell,
ATTORNEY

UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES BOOK.

Application filed July 5, 1922. Serial No. 572,776.

This invention relates to manifolding devices and with respect to its more specific features to manifolding books as sales books and the like.

5 One of the objects of the invention is the provision of a practical manifolding book in which may readily be utilized record leaves of different texture, thickness, hardness, or color, and wherein one of the record leaves 10 may be of substantial, durable material, the construction being such that only a minimum amount of transfer material is required.

15 Another object of the invention is the provision of a manifolding leaflet or unit in which one of the leaves is of a character to protect the other leaf.

20 Other objects will be in part obvious and in part pointed out hereinafter.

25 The invention accordingly consists in the features of construction, combinations of elements and arrangement of parts which will be exemplified in the construction hereinafter set forth, and the scope of the application of which will be indicated in the following claim.

30 In the accompanying drawings forming part of this specification and wherein similar reference characters refer to similar parts throughout the several views,

35 Fig. 1 is a perspective view illustrating a manifolding device embodying the invention; and

Fig. 2 is a plan view of Fig. 1, certain parts being broken away for clearer disclosure.

40 Referring now more specifically to the drawing the numeral 1 indicates a backing which may be of cardboard, pasteboard or other stiff material and which is hinged at one end 2 to a support leaf 3 of similarly stiff material. The support leaf 3 underlies the backing and extends out therefrom as indicated at 4, at a point remote from the hinge, the extension serving for the attachment of a pad of tissue leaves hereinafter referred to. The numerals 5 and 6 respectively indicate original and duplicate leaves going to make up a manifolding leaflet.

45 50 The underlying leaf 6 of the leaflet is adapted to receive inscription made upon the upper face of the leaf 5, suitable transfer material being utilized. The underlying leaf 6

55 besides being a record leaf is also a "stop" leaf; that is, it serves to prevent the transfer of inscription to any leaves underlying the same. To this end it is preferably made of relatively thick or heavy paper which also has a considerable degree of stiffness compared to the leaf 5. The leaf 5 is of soft 60 paper, and preferably opaque, and impression may readily be transferred therethrough. Portions of the leaves 5 and 6 are pasted together, as for instance indicated by the shaded area 7 at the ends of these 65 two leaves. For readily separating the leaves along a predetermined line, the leaf 5 may be weakened as indicated by the dotted line 8. Similarly, in order to readily divide the stiffer leaf 6, weakened lines 70 may be provided at various points as indicated at 9, 10, 11.

75 A pad may be made up of the leaves 5 and 6, and to this end a plurality of the combined record and stop leaves 6 are attached 80 together as by means of the staples 12, which pass through extended or stub portions of the leaves 6, the sets of leaves being in superposed relation, with the leaves 5 and 6 similarly superposed. The numeral 13 indicates a transfer leaf which may be bound 85 with the stub portions of the leaves 6, by the same staples 12. The weakened line 9 serves to permit the ready tearing of the main portion of the leaves 6 from the stub portions thereof.

90 The numerals 14 indicate several leaves of a second pad stapled to the extended end 4 of the support leaf 3. The leaves 14 may be of tissue paper and these leaves may be 95 placed in superposed relation with the leaves 5 and 6 and so as to lie upon the upper face of the transfer leaf 13. The invention viewed in some aspects admits of the use of a transfer leaf 13 in which the transfer material is only on the under face thereof. In the embodiment illustrated, however, both faces of the transfer leaf 13 are provided with transfer material, this leaf thus being a double-face transfer leaf.

100 To set the book for inscription, the leaf 5 is grasped at its outer end and drawn back by, as it were, rotating it around the weakened line 8. The transfer leaf 13 may be placed upon or will be found lying upon the 105 uppermost leaf 6. The bottom leaf of the

leaves 14 will be drawn forward to lie upon the transfer leaf 13, and thereupon the original leaf 5 will be returned so as to lie upon the then interposed tissue leaf. Inscription 5 made upon the original leaf 5 will be transferred to the duplicate leaf 6 and also to the underface of the interposed triplicate leaf 14. The backing 1 may now be turned upon the hinge 2 and the inscribed tissue leaf permitted to fall upon the support leaf 3 where it will be held and protected when the backing is returned into superposed relation therewith. The leaf 6 may be torn from its stub along the weakened line 9, and the 10 leaves 5 and 6 may readily be separated along the weakened line 8. The tearing of the leaf 6 along the line 9 and its removal from the pad permits the transfer leaf to lie upon the next under lying set of leaves 5 and 6, and 15 the book may be set for subsequent inscription by repeating the operations hereinbefore referred to.

By utilizing separate leaves 5 and 6, pasted together as described, the book may readily 20 be made to embody leaves of various character. The "hard" leaf 5 may be of a different color from the original leaf 5 and may be made of any thickness and hardness desired without detracting from the manifolding 25 character of the book. The leaflet, composed of the hard underleaf and soft upper leaf pasted together, is adapted for use in various manifolding books either by multiplying the leaflets or by associating extra leaves when 30 more copies at one writing are desired. Or 35 a single leaflet may be utilized alone in situations where more are not needed. The hard duplicate offers a smooth surface to support the softer leaf being written upon.

Thus by the above described construction 40 are accomplished among others the objects hereinbefore referred to.

As many changes could be made in the 45 above construction and many apparently widely different embodiments of this invention could be made without departing from the scope thereof, it is intended that all matter contained in the above description or shown in the accompanying drawings shall be interpreted as illustrative and not in a 50 limiting sense.

It is also to be understood that the language used in the following claim is intended 55 to cover all the generic and specific features of the invention, herein described, and all statements of the scope of the invention which, as a matter of language, might be said to fall therebetween.

Having described my invention, what I 60 claim as new and desire to secure by Letters Patent, is:

In a manifolding book of the character described, in combination, connected sets of three record leaves, the leaves of each set superposable relative to each other, with interposition of transfer material, to produce three inscribed leaves at one writing, the upper two of said relatively superposed leaves of each set being separate from and displaceable from each other and of manifolding paper, one of said two being of tissue paper and the other of opaque paper; the lowermost of the three leaves of each set being a combined record leaf and stop leaf directly pasted at one end to said opaque 70 leaf.

In testimony whereof I affix my signature.
EDWARD KIRBY BOTTLE.
